V. MAUCK,
MUNITION CASING,
APPLICATION FILED OCT. 8, 1918.

Patented Sept. 26, 1922.

FIG. I.

FIG. II.

FIG. III.

INVENTOR

VICTOR MAUCK.
by *John E. Fahey.*

ATTORNEY

UNITED STATES PATENT OFFICE.

VICTOR MAUCK, OF NORRISTOWN, PENNSYLVANIA.

MUNITION CASING.

Application filed October 8, 1918. Serial No. 257,354.

To all whom it may concern:

Be it known that I, VICTOR MAUCK, a citizen of the United States, residing at Norristown, in the county of Montgomery and 5 State of Pennsylvania, have invented a certain new and useful Improvement in Munition Casings, whereof the following is a specification, reference being had to the accompanying drawing.

10 The present invention is a modification of the inventions respectively described in my applications Serial 217,037 filed February 14, 1918, and Serial 219,674 filed February 28, 1918, for Letters Patent of the United 15 States, having as its object to provide a casing which may be hermetically sealed for the transportation of explosives but which may be tested for leakage at the joint between the casing body and its closure, by admission of compressed air to the interior of the casing after the latter is presumably hermetically sealed at said joint, and not only be readily opened to discharge its contents, but may be resealed; so that the casing can 20 be again used for the same purpose, as distinguished from ordinary munition casings which are provided with sealing means which are destroyed when the casing is opened, and are not provided with any leak- 25 age testing means.

As it is of the utmost importance, in the present state of war, to minimize the weight and size of all containers used in the transportation of munitions; it is the object of 30 my invention to not only provide a suitable removable closure for a munition casing, which closure may be made of thin pressed sheet metal, and, consequently, is far less weighty than if made of cast metal of the same strength, but to so shape the elements 35 of said closure as to occupy the minimum space.

The form of my invention hereinafter described comprises means for interlocking a 40 munition casing with a removable closure, so that the latter cannot be accidentally displaced, and includes the provision upon the munition casing of a flange which presents a downwardly turned ledge, to afford the 45 maximum security of engagement of the hooks which hold the closure upon the casing; and a closure including a pressed sheet metal lid, a pressed sheet metal yoke, and a lid clamping screw carried by said yoke,

which are not only so shaped as to afford 55 the maximum strength with minimum dimensions but permit said yoke to extend within a recess in said lid, and said screw to extend entirely within the outer boundaries of said yoke when the closure is in 60 position upon the casing. Moreover, a convenient adjunctive feature of my invention is the provision of means to seal the screw by which the closure is held on the casing, so that the casing cannot be opened without 65 breaking said seal and thus indicating the fact that it has been opened.

My invention includes the various novel features of construction and arrangement hereinafter more definitely specified. 70

In the drawing; Fig. I is a plan view of a munition casing embodying a convenient form of my invention.

Fig. II is a longitudinal sectional view of said casing, taken on the line II, II in 75 Fig. I.

Fig. III is a transverse, central sectional view of the yoke shown in Figs. I and II.

In said figures; the body of the munition casing is a cylindrical tubular shell 1. Said shell is preferably formed of a primarily plane sheet of commercial steel, electrically welded at a single longitudinal seam 2 and permanently closed by the bottom plate 3, having the cylindrical flange 4 united to 80 said shell 1, conveniently by an oxy-acetylene welding process. The opposite, upper, end of said shell 1 is preferably provided with an integral, outwardly and downwardly turned, annular flange 6 of semi-circular cross section, which affords a bearing for the resilient gasket 7, which may be of rubber or other suitable material. Said flange 6 forms a ledge which is hollow at 85 its under side to engage the hereinafter described closure hooks more securely than if said flange were plane. 90

The closure for said casing includes the lid 9, which is pressed from a primarily plane circular plate of sheet metal so as to 100 have the annular flange 10 opposed to the flange 6 on said shell and arranged to bear upon said gasket 7. Said lid 9 also has the cylindrical shoulder 12 adjoining its flange 10 and fitting in said shell, and has its intermediate portion 13 conically dished, with its rounded apex 14 extending in said shell, toward the closed end of the latter. Said lid 105

9 also has, in its dished portion 13, a test port 15 for detachable connection with a source of compressed air, formed by the internally screw threaded nipple 16, pressed from said lid 9, in unitary relation therewith, and extending into said shell. The tapered screw test plug 18, which is preferably provided with a standard pipe screw thread, is fitted to said nipple, and has a wrench hold accessible from the exterior of said lid 9, conveniently the slot 19 for a screw driver.

Said lid 9 is conveniently secured by the yoke 21 which, as shown in Fig. I, has a substantially rhombic body, with two diametrically opposite arms 22 having pendent, inwardly turned, hooks 23 in unitary relation therewith; the ends of said hooks being shaped to engage in the hollow of said hook ledge formed by said annular shell flange 6. Said yoke 21 is hollow, U-shaped in cross section, deeper at its middle than at its ends, and has its U flanges extending outwardly from said shell, oppositely to the direction of extension of said hooks 23.

It is to be noted that said yoke 21 is so proportioned and arranged with reference to said lid 9 as to fit within the latter to the maximum extent possible in view of their relative movement necessary to apply and remove them with respect to said shell.

Said yoke 21 has the outwardly extending rectangular central nut pocket 25, and opposite, inwardly extending, nut locking tabs 26, to rigidly hold the nut 27; the latter being of standard punched size. Such construction and arrangement is preferable on account of its low cost. However, it is to be understood that said yoke may be otherwise provided with a central nut or screw thread for engagement with the clamp screw 28 which extends through said yoke in registry with the apex 14 of said conical portion 13 of said lid 9. I prefer to provide said clamping screw 28 with a stop limiting the extent to which it may be normally withdrawn with reference to said yoke, and conveniently the cotter pin 30 extending through the hole 31 which is drilled transversely through said screw near its point. Said clamping screw 28 is preferably provided with the T head 32, conveniently of the rhombic shape shown in Fig. I, and having the transverse aperture 34 for the sealing wire 35 which extends through said head aperture and transversely encircles said yoke 21 and has its ends twisted together and imbedded in the seal 36, conveniently formed of lead or other soft metal; said wire and seal being employed to indicate whether the casing has remained unopened during its transportation or not.

It is to be understood that in the position shown in Fig. II, said casing is hermetically sealed by pressure of said screw 28 upon said

lid 9, compressing said gasket 7 at the joint between said casing flange 6 and the flange 10 of said lid; thus preventing access of air and moisture to the explosive material 37 in said casing. However, said screw 28 may be turned, by its head 32, until it is retracted to the limit permitted by the stop 30; whereupon, said closure lid and yoke may be applied to and removed from said casing by movement transversely with respect to the axis of the latter; said lid and yoke being then relatively movable, axially with respect to said casing, to the minimum extent permitting engagement of the yoke hooks 23, with said casing flange 6.

The casing chosen for illustration, but which is shown partly broken away, includes a shell which is six and one-half inches in internal diameter and has a depth of fifty-one inches, internally, between the apex of the lid and the bottom of the casing, and is designed to contain a double charge for propelling projectiles of the United States standard 155 millimeter howitzer. However, it is to be understood that casings embodying my invention may be made of different sizes and proportions. Therefore, said screw head 32 is preferably shaped as shown in Fig. I, to display symbols 38 indicating the nature and purpose of the contents of the casing, to facilitate the dispensation of the same. As access of moisture to such munitions would materially deteriorate the latter; the United States Government requires that the joint between the casing and its closure, which is supposed to be hermetically sealed, as above described, shall be subjected to an air pressure of five pounds per square inch for five minutes without leakage. Considerable difficulty has been experienced in affording a suitable connection for such a test, without materially increasing the cost of the casing, and the nipple and plug construction and arrangement above described has the advantage of affording a suitable test port at the least possible cost.

It is to be noted that the cooperative relation of the closure lid, yoke and clamping screw is not only such as to minimize the axial extent of the same, but to permit the head of the screw to come within the upper boundary of the yoke when the structure is assembled and permit the sealing means to be similarly secluded in the yoke and thus avoid any projecting parts which are apt to be displaced during the necessarily rough handling to which such casings are necessarily subjected in transportation overseas.

Of course, such closures as above described may be used on casings differing from the casing 1. Therefore, I do not desire to limit myself to the precise details of construction and arrangement herein set forth, as it is obvious that various modifications may be

made therein, without departing from the essential features of my invention as defined in the appended claims.

I claim:

- 5 1. In a munition casing, the combination with a cylindrical, tubular metal shell, permanently closed at one end, and having at the other end an outwardly and downwardly turned annular flange forming a hollow hook ledge, of semi-circular cross section; of a plane annular gasket, of resilient material, on said flange; a closure for said shell, including a pressed sheet metal lid, having a plane annular flange opposed to 70 the flange on said shell and arranged to bear upon said gasket; said lid having a cylindrical shoulder adjoining said flange and fitting in said shell, and having its intermediate portion conically dished and extending in said shell, toward the closed end of the latter, and having, in its dished portion, an internally screw threaded nipple, extending inwardly, with respect to said shell, in unitary relation with said lid, and forming a test port; a tapered screw test plug fitted 75 to said nipple, and having a wrench hold accessible from the exterior of said lid; a pressed sheet metal yoke having a rhombic body with two diametrically opposite arms having pendent, inwardly turned, hooks in 80 unitary relation therewith; the ends of said hooks being shaped to engage in the hollow of said hook ledge; said yoke being hollow, U-shaped in cross section, deeper at its middle than at its ends, and with its 85 U flanges extending outwardly from said shell; said yoke having an outwardly extending central nut recess, and inwardly extending nut locking tabs; a standard size nut, mounted in said recess and rigidly 90 locked in said yoke by said tabs; a clamp screw, extending in said nut, in opposition to said lid, having a stop hole extending in it, near its point, and having a head with an aperture for a sealing wire; a stop pin 100 in said hole, preventing withdrawal of said screw from said nut; and a sealing wire extending through said aperture, engaging said yoke, and normally preventing rotation of said screw; the construction and arrangement being such that said closure lid and yoke may only be applied to and removed from said casing when said screw is retracted to the extent limited by said stop pin, said closure being capable of being 105 hermetically clamped upon said casing by said screw, and, when thus clamped, said screw head is within said yoke.
3. In a munition casing, the combination with a tubular metal shell, permanently closed at one end, and having at the other end an outwardly and downwardly turned annular flange forming a hollow hook ledge; of an annular gasket, on said flange: a closure for said shell, including a pressed 115 sheet metal lid, having an annular flange opposed to the flange on said shell and arranged to bear upon said gasket; said lid having a shoulder adjoining said flange and fitting in said shell and having its intermediate portion dished and extending in 120 said shell, toward the closed end of the latter; a pressed sheet metal yoke having a rhombic body with two diametrically opposite arms having pendent, inwardly 125 turned, hooks in unitary relation therewith; the ends of said hooks being shaped to engage in the hollow of said hook ledge; said yoke being hollow, U-shaped in cross section, deeper at its middle than at its ends, and with its U flanges extending outwardly from said shell; said yoke having an outwardly extending central nut recess, and inwardly extending nut locking tabs; a standard size nut, mounted in said recess and rigidly 130 locked in said yoke by said tabs; a clamp screw, extending in said nut, in opposition to said lid, having a stop hole extending in it, near its point, and having a head with an aperture for a sealing wire; a stop pin in said hole, preventing withdrawal of said screw from said nut; and a sealing wire extending through said aperture, engaging said yoke, and normally preventing rotation of said screw; the construction and arrangement being such that said closure lid and yoke may only be applied to and removed from said casing when said screw is retracted to the extent limited by said stop pin, said closure being capable of being hermetically clamped upon said casing by said screw, and, when thus clamped, said screw head is within said yoke.
2. In a munition casing, the combination with a tubular metal shell, permanently closed at one end, and having at the other end an outwardly and downwardly turned

turned, hooks in unitary relation therewith; the ends of said hooks being shaped to engage in the hollow of said hook ledge; said yoke being hollow, U-shaped in cross section, deeper at its middle than at its ends, and with its U flanges extending outwardly from said shell; said yoke having an outwardly extending central nut recess, and inwardly extending nut locking tabs; a stand-
 10 ard size nut, mounted in said recess and rigidly locked in said yoke by said tabs; a clamp screw, extending in said nut, in opposition to said lid, having a stop hole extending in it, near its point, and having a head with an
 15 aperture for a sealing wire; a stop pin in said hole, preventing withdrawal of said screw from said nut; and a sealing wire extending through said aperture, engaging said yoke, and normally preventing rotation
 20 of said screw; the construction and arrangement being such that said closure lid and yoke may only be applied to and removed from said casing when said screw is retracted to the extent limited by said stop pin,
 25 said closure being capable of being hermetically clamped upon said casing by said screw, and, when thus clamped, said screw head is within said yoke.

4. In a munition casing, the combination
 30 with a tubular metal shell, having at one end an outwardly and downwardly turned annular flange forming a hollow hook ledge; of an annular gasket, on said flange; a closure for said shell, including a pressed sheet
 35 metal lid, having an annular flange opposed to the flange on said shell and arranged to bear upon said gasket; said lid fitting in said shell, and having its intermediate portion dished and extending in said shell; a
 40 metal yoke with two arms having pendent, inwardly turned, hooks shaped to engage in the hollow of said hook ledge; said yoke being hollow, U-shaped in cross section, deeper at its middle than at its ends, and with its
 45 U flanges extending outwardly from said shell; said yoke having a central nut recess, and nut locking tabs; a nut, mounted in said recess and rigidly locked in said yoke by said tabs; a clamp screw, extending in said
 50 nut, in opposition to said lid, having a stop near its point, and having a head with an aperture for sealing means preventing rotation of said screw; the construction and arrangement being such that said closure
 55 lid and yoke may only be applied to and removed from said casing when said screw is retracted to the extent limited by said stop, said closure being capable of being hermetically clamped upon said casing by said screw,
 60 and, when thus clamped, said screw head is within said yoke.

5. In a munition casing, the combination
 with a tubular metal shell, having at one end an outwardly and downwardly turned
 65 annular flange forming a hollow hook ledge;

of an annular gasket, on said flange; a closure for said shell, including a pressed sheet metal lid, having an annular flange opposed to the flange on said shell and arranged to bear upon said gasket; said lid fitting in said shell, and having its intermediate portion dished and extending in said shell; a metal yoke with two arms having pendent, inwardly turned, hooks shaped to engage in the hollow of said hook ledge; said yoke being hollow, U-shaped in cross section, deeper at its middle than at its ends, and with its U flanges extending outwardly from said shell; said yoke having a central nut recess, and nut locking tabs; a nut, mounted in said recess and rigidly locked in said yoke by said tabs; a clamp screw, extending in said nut, in opposition to said lid, having a stop near its point; the construction and arrangement being such that said closure lid and yoke may only be applied to and removed from said casing when said screw is retracted to the extent limited by said stop, said closure being capable of being hermetically clamped upon said casing by said screw, and, when thus clamped, said screw head is within said yoke.

6. In a munition casing, the combination with a tubular metal shell, having at one end an outwardly turned annular flange forming a hook ledge; of an annular gasket, on said flange; a closure for said shell, including a metal lid, having an annular flange opposed to the flange on said shell and arranged to bear upon said gasket; said lid fitting in said shell, and having its intermediate portion dished and extending in said shell; a metal yoke with two arms having pendent, inwardly turned, hooks shaped to engage said hook ledge; said yoke being a channel bar deeper at its middle than at its ends, and with its flanges extending outwardly from said shell; said yoke having central nut locking means; a nut, secured in said yoke by said locking means; a clamp screw, extending in said nut, in opposition to said lid; the construction and arrangement being such that said closure lid and yoke may only be applied to and removed from said casing when said screw is retracted, and said closure being capable of being hermetically clamped upon said casing by said screw.

7. In a munition casing, the combination with a tubular metal shell, having at one end an outwardly turned annular flange forming a hook ledge; of an annular gasket, on said flange; a closure for said shell, including a metal lid, having an annular flange opposed to the flange on said shell and arranged to bear upon said gasket; a metal yoke with two arms having pendent, inwardly turned, hooks shaped to engage said hook ledge; said yoke being a channel bar deeper at its middle than at its ends, and with its

flanges extending outwardly from said shell; said yoke having central nut locking means; a nut, secured in said yoke by said locking means; a clamp screw, extending in said nut, 5 in opposition to said lid; the construction and arrangement being such that said closure lid and yoke may only be applied to and removed from said casing when said screw is retracted, and said closure being capable of being hermetically clamped upon 10 said casing by said screw.

8. In a munition casing, the combination with a tubular metal shell, having at one end an outwardly and downwardly turned 15 annular flange forming a hook ledge; of an annular gasket, on said flange; a closure for said shell, including a metal lid, having an annular flange opposed to the flange on said shell and arranged to bear upon said gas- 20 ket; said lid having a cylindrical shoulder adjoining said flange and fitting in said shell, and having its intermediate portion conically dished and extending in said shell, toward the closed end of the latter, and hav- 25 ing, at its dished portion, an internally screw threaded nipple, extending inwardly, with respect to said shell, in unitary relation with said lid, and forming a test port; a tapered screw test plug fitted to said nipple, and 30 having a wrench hold accessible from the exterior of said lid; a pressed sheet metal yoke having a rhombic body with two diametrically opposite arms having pendent, inwardly turned, hooks shaped to engage 35 said hook ledge; said yoke being hollow, U- shaped in cross section, deeper at its middle than at its ends, and with its U flanges extending outwardly from said shell; said yoke having a central nut; a clamp screw, 40 extending in said nut, in opposition to said lid; the construction and arrangement being such that said closure lid and yoke may only be applied to and removed from said casing when said screw is retracted, and said 45 closure being capable of being hermetically clamped upon said casing by said screw.

9. In a munition casing, the combination with a tubular metal shell, having at one end an outwardly and downwardly turned 50 annular flange forming a hook ledge; of an annular gasket, on said flange; a closure for said shell, including a metal lid, having an annular flange opposed to the flange on said shell and arranged to bear upon said gas- 55 ket; a pressed sheet metal yoke having a rhombic body with two diametrically opposite arms having pendent, inwardly turned, hooks shaped to engage said hook ledge; said yoke being hollow, U-shaped in cross sec- 60 tion, deeper at its middle than at its ends, and with its U flanges extending outwardly from said shell; said yoke having a central nut; a clamp screw, extending in said nut, in opposition to said lid; the construction 65 and arrangement being such that said clo-

sure lid and yoke may only be applied to and removed from said casing when said screw is retracted, and said closure being capable of being hermetically clamped upon 70 said casing by said screw.

10. In a munition casing, the combination with a tubular metal shell, having at one end an annular flange forming a hook ledge; of an annular gasket, on said flange; a closure for said shell, including a pressed sheet 75 metal lid, having an annular flange opposed to the flange on said shell and arranged to bear upon said gasket; said lid having its intermediate portion dished and extending in said shell, and having, extending in its 80 dished portion, a pressed sheet metal yoke with two diametrically opposite arms having pendent, inwardly turned, hooks in unitary relation therewith; the ends of said hooks being shaped to engage said hook 85 ledge; said yoke being hollow, U-shaped in cross section, wider and deeper at its middle than at its ends, with its U-flanges extending outwardly from said shell, and having a central nut; and a clamp screw, extending 90 in said nut, in opposition to said lid; the construction and arrangement being such that said closure lid and yoke may only be applied to and removed from said casing when said screw is retracted, said closure 95 being capable of being hermetically clamped upon said casing by said screw, and, when thus clamped, said screw is entirely within said yoke.

11. In a munition casing, the combination 100 with a tubular metal shell; of a closure for said shell, including a pressed sheet metal lid, having its central portion dished and extending in said shell, and having, secluded in its dished portion and below the top of 105 said shell, an internally screw threaded nipple, extending inwardly, with respect to said shell, formed of the pressed sheet metal, in unitary relation with said lid, and forming a test port through which communication 110 may be established between the interior and exterior of said shell; a tapered screw test plug fitted to said nipple, and having a wrench hold accessible from the exterior of said lid but below the top of said shell; and 115 means covering said port and plug arranged to removably secure said closure on said shell, in hermetical relation; whereby the joint between said shell and closure may be tested for leakage, by air pressure applied 120 through said port, and the casing be thereafter hermetically closed, with said plug, without disturbing said joint.

12. In a munition casing, the combination 125 with a tubular metal shell; of a closure for said shell, including a lid having its central portion dished and extending in said shell, and having secluded in its dished portion and within said shell, an internally screw threaded port; a tapered screw test plug 130

also within said shell fitted to said port, and having a wrench hold accessible from the exterior of said lid; and means arranged to removably secure said closure on said shell; whereby the joint between said shell and closure may be tested for leakage, by air pressure applied through said port, and the casing be thereafter hermetically closed, with said plug, without disturbing said

10 joint.

13. In a munition casing, the combination with a tubular metal shell, having at one end an outwardly turned annular flange forming a hook ledge; of an annular gasket, 15 on said flange; a closure for said shell, including a lid, having an annular flange opposed to the flange on said shell and ar-

ranged to bear upon said gasket; a pressed sheet metal yoke having, in unitary relation, arms with hooks fitted to engage said shell 20 flange; said yoke being hollow, U-shaped in cross section, deeper at its middle than at its ends, and with its U flanges extending outwardly from said shell; and, a clamp screw, extending through said yoke, in op- 25 position to said lid.

In testimony whereof, I have hereunto signed my name at Norristown, Pennsylvania, this third day of August, 1918.

VICTOR MAUCK.
